Primary Examiner — Bridget L Eland(74) *Attorney, Agent, or Firm* — Capitol City TechLaw(57) **CLAIM**

The ornamental design for an electric connector, as shown and described.

DESCRIPTION

FIG. 1 is a top, front, and right side perspective view of an electric connector showing my new design;

FIG. 2 is a top, rear, and right side perspective view thereof;

FIG. 3 is a bottom, front, and right side perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a top, front, and right side perspective view of a coupling part shown in FIGS. 1-9;

FIG. 11 is a top, rear, and right side perspective view thereof; and,

FIG. 12 is a bottom, front, and right side perspective view thereof.

The dashed broken lines in the figures show portions of the electric connector that form no part of the claimed design. The dot-dashed broken lines in the figures depict the bounds of the claim and form no part thereof.
